UNITED STATES PATENT OFFICE.

EBERHARD FABER, OF NEW YORK, N. Y.

DESIGN FOR A PENCIL-POINT PROTECTOR.

Specification forming part of Design No. 6,192, dated October 8, 1872.

To all whom it may concern:

Be it known that I, EBERHARD FABER, of the city, county, and State of New York, have invented a new and ornamental Design for a Pencil-Point Protector; and I do hereby declare the following to be a full, clear, and exact description thereof, which will enable those skilled in the art to make and use the same, reference being had to the accompanying drawing forming part of this specification, which drawing represents a side view of this invention.

The design is to impart an ornamental appearance to pencil-protectors which have a longitudinal slot extending from one end to or about its center. It consists of a cylinder open at one end and having a convex head, and ornamented by grooves or depressions, whereby is imparted to the article a beautiful, ornamental, and pleasing appearance.

In the drawing, the letter A designates the pencil-protector, it being a tube of uniform diameter throughout its length, open at one end, and closed at the opposite end by a convex head, a, formed thereon, and ornamented by annular grooves or depressions b b, as shown. This cylinder is further ornamented by the slots c and circular eye d, but such is not claimed.

Having thus described my design, what I claim is—

The design for pencil-protector, consisting of the hollow cylinder A, formed with the grooves or depressions b b, and the closed convex head a, as herein shown.

EBERHARD FABER.
